US00D646918S

(12) **United States Design Patent**
Wynalda, Jr. et al.

(10) **Patent No.:** **US D646,918 S**
(45) **Date of Patent:** ** *Oct. 18, 2011

(54) **MEDIA DISC STORAGE CONTAINER**

(76) Inventors: **Robert M. Wynalda, Jr.**, Comstock Park, MI (US); **Robert G. Rajter, Jr.**, Rockford, MI (US)

(*) Notice: This patent is subject to a terminal disclaimer.

(**) Term: **14 Years**

(21) Appl. No.: **29/336,212**

(22) Filed: **Apr. 29, 2009**

(51) LOC (9) Cl. **06-04**

(52) U.S. Cl. **D6/632; D6/407**

(58) **Field of Classification Search** D6/407, D6/510, 626-635; D9/415, 418, 420, 422-426, D9/428, 432-433; D19/26-27; 206/307, 206/307.1, 308.1, 309-313, 308.2, 308.3, 206/445, 387.15, 749, 751; D3/273, 294, D3/295, 299-301, 303-304, 218, 201, 270, 312/9.1, 902, 9.9, 9.48, 9.55, 9.64, 9.47, 312/9.53; D14/478-479; 40/495; 434/404

OTHER PUBLICATIONS

Office action in related U.S. Appl. No. 12/366,456, filed Feb. 5, 2009 (the published application has cited in earlier IDS).

Primary Examiner — T. Chase Nelson

(74) Attorney, Agent, or Firm — Zollinger & Burleson, Ltd.

(57) **CLAIM**

The ornamental design for the media disc storage container, as shown and described.

DESCRIPTION

FIG. 1 is a perspective view of a media disc storage container in an open configuration;

FIG. 2 is a perspective view of the media disc storage container of FIG. 1 in a closed configuration;

FIG. 3 is a front elevation of FIG. 1;

FIG. 4 is a rear elevation of FIG. 1;

FIG. 5 is a left side view of FIG. 3;

FIG. 6 is a right side view of FIG. 3;

FIG. 7 is a top plan view of FIG. 3; and,

FIG. 8 is a bottom plan view of FIG. 3.
